MISSILE BOOSTER

Stanley Lehrer, Pompton Lakes, N.J., assignor to Thiokol
Chemical Corporation, Bristol, Pa., a corporation of
Delaware

Filed Feb. 17, 1961, Ser. No. 63,970

Term of patent 14 years

(Cl. D71—1)

Fig. 3

Fig. 4

FIGURE 1 is a side elevation of a missile booster showing my new design, all sides thereof being the same in appearance as indicated in FIGURE 2;

FIGURE 2 is a cross-sectional view thereof taken on the line 2—2 of FIGURE 1 in the direction of the arrows;

FIGURE 3 is an enlarged fragmentary perspective view illustrating, in detail, several of the rocket motors arranged around the circumference of the missile booster as shown in FIGURE 1; and

FIGURE 4 is a vertical cross-section through one of the rocket motors on the enlarged scale shown in FIGURE 3.

The bottom of the missile is an unornamented plane surface.

The dominant features of my design reside in the portions shown in full lines.

I claim:

The ornamental design for a missile booster, as shown and described.
